UNITED STATES PATENT OFFICE.

JOSEPH DUBISEE, OF PHILADELPHIA, PENNSYLVANIA, ASSIGNOR OF ONE-HALF TO
FRANCIS J. LAMBERT, OF PHILADELPHIA, PENNSYLVANIA.

CUSHIONED SUPPORT FOR STAMPING DEVICES.

943,342.

Specification of Letters Patent. Patented Dec. 14, 1909.

Application filed June 5, 1909. Serial No. 500,272.

To all whom it may concern:

Be it known that I, JOSEPH DUBISEE, a citizen of the United States, and a resident of the city and county of Philadelphia, State of Pennsylvania, have invented an Improvement in Cushioned Supports for Stamping Devices, of which the following is a specification.

My invention has reference to cushioned supports for stamping devices, and consists of certain improvements fully set forth in the following specifications and shown in the drawings which form a part thereof.

Dating stamps used in railroad ticket offices, in their operation are subject to considerable jar which creates unpleasant noises when struck and also tires the operator on account of the non-yielding character of the machine. To overcome these difficulties, it has been customary in some cases to employ a soft rubber or felt pad which rests upon the table or counter and upon which the dating stamp is placed, the said pad acting as a means to deaden the sound and to give a yielding support to the dating stamp to reduce the strain upon the operator when striking the stamp. In other cases, the head of the movable hammer or platen of the dating stamp has been covered with a rubber cap or head which is struck by the hand.

The latter construction is not satisfactory, since it does not deaden the noise due to vibration of the dating stamp upon the table or counter, and the former is objectionable in that it is expensive and necessitates being separately handled when moving the dating stamp from place to place upon the counter.

The object of my invention is to provide a cushion support for a dating or other stamping device which may be readily applied or detached and which becomes part of the stamping machine in use so as to be moved with the machine when it is moved from place to place. Moreover it is the object of my invention to provide a construction which is exceedingly effective and inexpensive.

My invention consists of a wire clamping device, adapted to clamp upon the base portions or other parts of the stamp, and having holding portions provided with feet of yielding material upon which the dating stamp rests.

My invention also comprehends details of construction which, together with the fea-

tures above specified, will be better understood by reference to the drawings, in which:

Figure 1 is a side elevation of a dating stamp having my improved cushion supports supplied thereto; Fig. 2 is an inverted 60 plan view of a portion of the same; Fig. 3 is a perspective view of my improved cushion support, removed from the dating stamp; and Fig. 4 is an elevation of one of the cushion feet removed.

A is the stamping device and is provided with the base portions B, B which have flanges C. The stamping device may be of any suitable character, the form shown being the ordinary dating stamp generally used in railroad ticket offices.

My improvement may be considered as being fully disclosed in Fig. 3, which shows the general construction of one of the cushion devices D removed from the stamping machine. Referring to this structure, E is a wire frame which, at its middle portion, is bent upward into the hooked shape jaw F and also at its end portions bent into hook shape jaws H, H. The intermediate portions of the wire between jaws H and F are twisted into loops G, and the extreme end portions of the wire are bent into loops I. A spring J may be connected with the loops I so as to draw the two jaws H, H toward each other.

K, K are feet of rubber or other yielding material and these are forced through the looped portions G, and provided at their top with flanged portions L, upon which the bottom of the base B of the dating stamp rests. These yielding feet K may be provided with annular grooves M into which the ring portion G of the wire frames snaps, and by which the elastic or cushion feet are held to the frame.

The frame structure, together with the elastic feet above described and as shown in Fig. 3, is pushed onto the flange portions C of the base B of the dating stamp, as 100 indicated in Figs. 1 and 2. When this is done, the jaw F clamps over the end flange and the jaws H, H clamp over the side flanges of the base and are held tightly thereon by the coil-spring J. The base of 105 the dating stamp rests directly upon the flange portions L of the elastic feet K; and when the device is in position upon the dating stamp, it is evident that these cushion feet cannot jar out or become separated from 110

the wire frame E. Ordinarily, two of the cushion supports D shown in Fig. 3, would be employed with a dating stamp and this would be the case whether the base of the stamp was provided with two independent bases B, B or whether it had one large flanged base.

I have shown my cushion support in the form which I have found well adapted for the purposes for which my invention is intended, but it is evident that the wire structure may be bent or twisted into other forms or shapes while supporting the rubber or elastic feet and hence I do not restrict myself to the particular shape shown, as the illustration given is to be taken as an example of the nature of my invention rather than as a limitation thereof. It is also evident that, while the coil spring J is desirable, it is not essential, because the wire frame E may be made of such strength that the coil parts G may constitute spring portions for insuring the clamping jaws H, H clamping the flanged base of the dating stamp stamped. This spring action while advantageously secured by the structure of the wire frame E itself, is nevertheless improved and made more positive by the use of the coil-spring chain. The shapes of the jaws F and H and also the general shape of the frame E may be varied to suit the bases of the different stamping machines to which my improvement might be applied, without departing from the spirit of the invention; and likewise each of the frames may be provided with a plurality of the elastic or cushion feet to suit the duty required of the device, and I, therefore, do not restrict myself to the details of the invention.

Having now described my invention, what I claim as new and desire to secure by Letters Patent, is:

1. In a cushion support for stamping machines, a wire frame having upwardly extending overhanging clamping jaws, combined with a plurality of downwardly extending yielding feet secured to said frame.
2. In a cushion support for stamping machines, a wire frame having upwardly extending overhanging clamping jaws and also having a plurality of looped portions, combined with a plurality of downwardly extending yielding feet secured to the looped portions of said frame.
3. In a cushion support for stamping machines, a wire frame having a plurality of upwardly extending clamping jaws and looped portions intermediate of the jaws, combined with downwardly extending cushion

feet having annular grooves to receive the looped portions of the frame and having flanged portions extending above the looped portions of the frame.

4. In a cushion support for stamping machines, a wire frame having a plurality of upwardly extending clamping jaws and looped portions intermediate of the jaws, combined with downwardly extending cushion feet having annular grooves to receive the looped portions of the frame and having flanged portions extending above the looped portions of the frame, and a spring device for drawing two of the clamping jaws toward each other. 75

5. In a cushion support for stamping devices, a wire frame bent into substantially U shape and having its middle portion bent into an upwardly extending jaw and its end portions also bent into upwardly extending jaws, combined with elastic portions secured to the frames intermediate of the jaws and extending downward and away from the jaws. 80

6. In a cushion support for stamping devices, a wire frame bent into substantially U shape and having its middle portion bent into an upwardly extending jaw and its end portions also bent into upwardly extending jaws, combined with elastic portions secured to the frames intermediate of the jaws and extending downward and away from the jaws, and a coiled spring for drawing the two end jaws toward each other. 85

7. A cushion support for a dating stamp consisting of a metal frame having a plurality of upwardly extending overhanging clamping jaws, combined with a plurality of downwardly extending elastic feet widely separated. 90

8. A cushion support for a dating stamp consisting of a metal spring frame made of bent wire having a plurality of upwardly extending and overhanging clamping jaws, combined with a plurality of downwardly extending elastic feet widely separated. 100

9. A cushion support for a dating stamp consisting of a metal frame having a plurality of upwardly extending overhanging clamping jaws and also a plurality of looped portions, combined with a plurality of independent downwardly extending elastic feet removably secured respectively to the looped portions of the metallic plate. 110

In testimony of which invention, I here- 115 unto set my hand.

JOSEPH DUBISEE.
